UNITED STATES PATENT OFFICE.

JOHN H. BELLAMY, OF CHARLESTOWN, MASS., ASSIGNOR TO SAMUEL D. NILES AND BENJAMIN A. WARD.

DESIGN FOR A CLOCK-FRONT.

Specification forming part of Design No. 4,375, dated October 4, 1870.

To all whom it may concern:

Be it known that I, JOHN H. BELLAMY, of Charlestown, in the county of Middlesex and State of Massachusetts, have originated and designed a new and useful Pattern for Clock-Fronts, of which the following is a full and exact description, reference being had to the accompanying photograph making a part of the specification.

The nature of my invention consists of a clock-front, the outside showing two pillars, A A, surmounted by an arch, B, inclosing a key-stone, C, the whole inclosing dial, pendulum, sash, and combination of emblems, as follows:

D represents the dial, above which are the square E and compass F, the two inclosing the

letter "G." On the right of square and compass are a pick, H, shovel I, and bar J; on the left of the square and compass a mallet, K, and a chisel, L. Below the dial D are an hour-glass, M, and sash N, inclosed by wings O, on the right of which is a three-round ladder, P, and on the left of the wings two parallels, R R, inclosing a book, S, and a circle, T.

What I claim, and desire to secure by Letters Patent, is—

The design for a clock-front herein set forth.

JOHN H. BELLAMY.
